CUTTING ATTACHMENT

Filed Oct. 3, 1928

SANUEL E. SANDERSON
INVENTOR

BY *Victor J. Evans*

ATTORNEY

WITNESS:

UNITED STATES PATENT OFFICE

SAMUEL E. SANDERSON, OF BROOKLYN, NEW YORK

CUTTING ATTACHMENT

Application filed October 3, 1928. Serial No. 310,122.

This invention relates to improvements in cutting attachments for sewing machines for the purpose of cutting cloth, paper and the like.

5 The primary object of the invention resides in a scissors attachment for sewing machines which includes a stationary blade and a co-acting movable blade, the latter being operable by the reciprocation of the needle bar to 10 which it is operably connected, there being work feeding means also operable by the needle bar to automatically feed the work to the knives during operation of the same.

Another object is to utilize the reciprocating movements of the needle bar of a sewing machine to operate a scissors attachment to effect a great saving in time and labor.

A further object is to provide a scissors attachment for adjustment to sewing machines 20 of different makes.

With these and other objects in view, the invention resides in certain novel construction and combination and arrangement of parts, the essential features of which are 25 hereinafter fully described, are particularly pointed out in the appended claims, and are illustrated in the accompanying drawing, in which:—

Figure 1 is a side elevation showing one of 30 its extreme positions of the parts in full lines and the other extreme position in dotted lines.

Figure 2 is a top plan view.

Figure 3 is a vertical transverse sectional 35 view on the line 3—3 of Figure 1.

Figure 4 is a reverse side elevation showing the feed wheels in a raised position.

Referring to the drawing by reference 40 characters, the numeral 10 designates a work rest which is substantially U-shape in plan and has a fixed plate 11 secured to one of its legs and a laterally adjustable plate 12 mounted on the underside of the other leg, the adjustment being obtained by transversely 45 slotting the leg as at 13 and passing adjusting screws 14 therethrough. The outer longitudinal edges of the plates 11 and 12 are bevelled as at 15. The plate 12 is adjusted relatively to the plate 11 to adapt the same for attachment to a sewing machine in lieu of the usual

front shuttle slide therefor. A straight horizontally disposed stationary blade 16 is fixedly attached to the inside of one of the legs of the work rest and has its cutting edge disposed above the top of the rest for co-action with a movable blade 17 pivoted thereto as at 18. The movable blade is provided with a rearwardly extending angular arm 19 terminating in a right angular disposed ear 20 having an elongated slot 21 therein and abutting the ear 20 is the angular end of a forked arm 22, while an adjusting screw 23 passes through the slot and threads into the arm whereby the forked arm may be laterally adjusted to a position to lie flat against the lower end of the needle bar 24 of a sewing machine to which it is attached. A set screw 25 passes through the bifurcation in the forked arm and threads into the needle bar to hold the said arm loosely thereagainst.

Fixedly supported by the work rest is a bracket 26 which rises upwardly and extends forwardly and to which a bell-crank lever 27 is pivoted. One arm of the bell crank extends rearwardly and is operatively connected to the movable blade 17 by a link 27'. The other short arm of the bell-crank extends downward and is slotted as at 28 to receive a bolt 29 which also passes through a slot 30 in a bracket arm 31. The lower end of the bracket arm serves as a bearing for a stub shaft 32 on which spaced feed wheels 33 are fixedly mounted and which have their peripheries provided with teeth or other friction surface 34. The wheels rest upon the work rest 10 to feed the work past the scissors during operation of the needle bar 24. Also fixed to the stub shaft 32 is a ratchet wheel 35 with which a dog or pawl 36 pivoted to the bracket arm engages. The tail of the dog is spring pressed as at 37 to normally hold the nose of the same in operative position against the ratchet wheel. The dog imparts retrograde movement to the ratchet wheel and stub shaft to turn the feed wheels in a clock-wise direction and prevents retrograde movement of the same. The dog is actuated by the reciprocations of the needle bar and the several operatively connected parts.

Pivoted to the bracket 26 is a lifting lever 100

38 in which the stub shaft 32 is also journaled and which terminates at its outer free end in a finger grip 39. The inner end of the lever abuts a leaf spring 40 which tends to place a tension thereon to hold the lever either in an operative down position or an inoperative raised position, the latter position being shown in full lines in Figure 4 of the drawing. The entire feed and ratchet wheel assembly may be raised and lowered as desired.

In practice, the cutting attachment is applied to a sewing machine by substituting the same for the front shuttle slide and is operatively connected to the needle bar as clearly shown and described. During running of the sewing machine, the needle bar reciprocates which rocks the movable knife blade 17 and any cloth, paper or the like fed past the blades will be cut thereby. Intermittent movement is imparted to the ratchet wheel 35 upon rocking of the knife blade 17, the dog 36 turning the ratchet wheel a predetermined distance on the downward stroke of the needle bar, and idling upon the up stroke thereof. It will therefore be seen that an operator need only to guide the material past the scissors after starting the sewing machine in operation, which will be found 30 a great saving in time and labor.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

40 What is claimed as new is:—

1. In combination with the reciprocable needle bar of a sewing machine, a cutting attachment comprising a stationary knife blade, and a co-acting pivoted blade operatively connected to said needle bar, and work feeding means operatively connected to said pivoted blade for automatically feeding a piece of work between said stationary blade and said movable blade during movement of 50 the latter.

2. In combination with the reciprocable needle bar of a sewing machine, a cutting attachment therefor comprising a stationary blade, a co-acting pivoted movable knife blade operatively connected to said needle bar to be rocked upon reciprocation thereof, and a rotary toothed element operable upon the rocking movements of said movable knife blade for feeding a piece of work to said knife 60 blades.

3. In combination with the reciprocable needle bar of a sewing machine, a cutting attachment therefor comprising a stationary blade, a co-acting pivoted movable knife 65 blade operatively connected to said needle

bar to be rocked upon reciprocation thereof, and intermittent work feeding means operable upon the rocking movements of said movable knife blade, said intermittent work feeding means including rotatable toothed feed wheels, and ratchet mechanism for imparting turning movements to said feed wheels.

4. In combination with the reciprocable needle bar of a sewing machine, a cutting attachment therefor comprising a work rest, attaching plates carried thereby, one of which is laterally adjustable for mounting upon a sewing machine in lieu of the front shuttle slide, a stationary knife blade fixedly attached to said work rest, a co-acting movable knife blade pivoted to said stationary knife blade, and adjustable means operatively connecting said movable knife blade with said needle bar.

5. A cutting attachment for sewing machines comprising a work rest, a stationary knife blade fixedly mounted thereon, and a co-acting movable knife blade pivoted to said stationary knife blade, said movable knife blade having an extension adapted to be operatively connected to the reciprocable needle bar of a sewing machine by which rocking movements may be imparted to said movable knife blade, work feed wheels journaled above said work rest for feeding a piece of work thereover, and means operable by the rocking movements of said movable knife blade for imparting intermittent movement to said feed wheels in one direction.

6. A cutting attachment for sewing machines comprising a work rest, a stationary knife blade fixedly mounted thereon, pivot means carried by said stationary blade, and a co-acting movable knife blade pivoted on said means and having an extension adapted to be operatively connected to the reciprocable needle bar of a sewing machine for moving said pivoted blade to cut a work piece positioned on said rest.

7. A cutting attachment for sewing machines comprising a work rest, a stationary knife blade fixedly mounted thereon, and a co-acting movable knife blade pivoted to said stationary knife blade, said movable knife blade having an extension adapted to be operatively connected to the reciprocable needle bar of a sewing machine by which rocking movements may be imparted to said movable knife blade, work feed wheels journaled above said work rest for feeding a piece of work thereover, and means operable by the rocking movements of said movable knife blade for imparting intermittent movement to said feed wheels in one direction, said means including a ratchet mechanism to which motion is imparted through a bell crank lever and operatively connected links.

8. A cutting attachment for sewing machines comprising a work rest, a stationary knife blade fixedly mounted thereon, and a

co-acting movable knife blade pivoted to said stationary knife blade, said movable knife blade having an extension adapted to be operatively connected to the reciprocable needle bar of a sewing machine by which 5 rocking movements may be imparted to said movable knife blade, work feed wheels journalled above said work rest for feeding a piece of work thereover, and means operable 10 by the rocking movements of said movable knife blade for imparting intermittent movement to said feed wheels in one direction, and means for supporting said feed wheels in an operative position against said work rest or 15 in an inoperative position out of engagement therewith.

9. A cutting attachment for sewing machines comprising a substantially U-shape work rest, attaching plates carried by said 20 work rest, one of which is laterally adjustable, a stationary knife blade mounted on the inside of one of the legs of said U-shape work rest, and a co-acting movable blade pivoted to said stationary blade, said movable 25 blade being provided with an extension for connecting with the reciprocable needle bar of a sewing machine to impart rocking movements thereto.

10. A cutting attachment for sewing machines comprising a substantially U-shape work rest, attaching plates carried by said 30 work rest, one of which is laterally adjustable, a stationary knife blade mounted on the inside of one of the legs of said U-shape work rest, and a co-acting movable blade pivoted to said stationary blade, said movable 35 blade being provided with an extension for connection with the reciprocable needle bar of a sewing machine to impart rocking movements thereto, a bracket rising from said 40 work rest, a lever pivoted to said bracket, a pair of work feed wheels journalled in said lever and adapted to respectively engage the legs of the U-shape work rest, and means 45 for imparting intermittent movement to said work feed wheels from the rocking movements of said movable knife blade.

11. A cutting attachment for sewing machines comprising a substantially U-shape 50 work rest, attaching plates carried by said work rest, one of which is laterally adjustable, a stationary knife blade mounted on the inside of one of the legs of said U-shape work rest, and a co-acting movable blade pivoted 55 to said stationary blade, said movable blade being provided with an extension for connection with the reciprocable needle bar of a sewing machine to impart rocking movements thereto, a bracket rising from said 60 work rest, a lever pivoted to said bracket, a pair of work feed wheels journalled in said lever and adapted to respectively engage the legs of the U-shape work rest, and means for 65 imparting intermittent movement to said work feed wheels from the rocking move-

ments of said movable knife blade, and spring means acting upon said lever to support the same in either a raised or lowered position with the feed wheels either in or out of engagement with said work rest.

In testimony whereof I have affixed my 70 signature.

SAMUEL E. SANDERSON.
